UNITED STATES PATENT OFFICE.

ALBERT BRUCE TUCKER, OF BIRMINGHAM, ALABAMA.

STORAGE CRATE CASE.

Application filed November 6, 1922. Serial No. 599,352.

To all whom it may concern:

Be it known that I, ALBERT BRUCE TUCKER, a citizen of the United States, residing at Birmingham, in the county of Jefferson and State of Alabama, have invented new and useful Improvements in Storage Crate Cases, of which the following is a specification.

This invention relates to receptacles and 10 has for its object the provision of a novel case designed to receive a crate of eggs or other commodity and adapted to be hermetically sealed whereby to exclude any moisture, the case and its contents being intended to be subsequently placed in cold 15 storage.

An important object is the provision of a 20 device of this character which will operate to preserve the contents inasmuch as moisture and air cannot gain access thereto, means being furthermore provided for forming air spaces about the cases when they are stacked.

An additional object is the provision of a 25 device of this character which will be simple and inexpensive in manufacture, efficient in use, durable in service and a general improvement in the art.

With the above and other objects and advantages in view the invention consists in the details of construction to be hereinafter more fully described and claimed and illustrated in the accompanying drawings, in which:

35 Figure 1 is a perspective view of the device,

Figure 2 is a longitudinal section and

Figure 3 is cross section.

Referring more particularly to the drawings I have shown my case as comprising 40 a rectangular casing including a bottom 10 and a hollow wall 11 which defines a continuous air space 12. The top of the wall is solid as indicated at 13 and is formed 45 with an inwardly extending projection 14 at its upper edge, which projection is formed with a groove or channel 15.

This casing is provided at its corners and 50 at the centers of its sides with vertically extending cleats 16 which terminate flush with the top edge but which project below the bottom thereof, the bottom of the case being provided at the lower ends of these 55 cleats with short horizontally extending cleats or blocks 17.

At the ends of the case I provide hori-

zontal cleats 18 which are located between the end cleats near the upper ends thereof to constitute finger holds or handles which will facilitate handling the device without 60 danger of its slipping from the operator's fingers.

The top of this casing is normally closed by a lid or cover 19 which is removable and which is formed at intervals with ears 20 65 provided with holes 21 which receive bolts 22 extending upwardly from the top of the case, these bolts carrying wing nuts 23. The underside of this lid or cover is formed with a flange 24 which fits conformingly 70 within the groove or channel 15.

In the use of the device the crate of eggs or other perishable commodity is placed within the case, the cover 19 is placed in position and the nuts 23 are tightened to clamp 75 it in place. The engagement of the flange 24 within the channel or groove 15 will make an air tight joint so that moisture and air cannot enter the casing and gain access to the material or articles being preserved.

A very important feature is the provision of the vertical cleats 16 and the bottom cleats or blocks 17, the former operating to define continuous vertical air spaces when 85 a large number of the cases are stacked and the cleats 17 operating to define holder passages or air spaces. It is of course very highly desirable that these air spaces be provided as they will permit free circulation 90 of air around each and every case and thus prevent mustiness, moulding, sweating or other injurious action.

From the foregoing description and a study of the drawings it will be apparent 95 that I have thus provided a simply constructed and consequently inexpensive storage case which will be highly efficient for the purpose specified and which will be a distinct improvement in every way.

While I have shown and described the preferred embodiment of the invention it is of course to be understood that I reserve the right to make such changes in the form, construction and arrangement of parts as 100 will not depart from the spirit of the invention or the scope of the subjoined claims.

Having thus described my invention I claim:

1. A device of the character described 110 comprising a casing open at its top and having its upper edge formed with a con-

tinuous channel, a cover fitting upon the casing and having its underside formed with a continuous flange seating within said channel, and means for clamping the cover onto the casing, consisting of upwardly extending bolts carried by the upper edge of the casing, ears on the cover formed with holes receiving said bolts, and wing nuts on said bolts.

10 2. A storage case comprising a casing including a bottom and a hollow wall defining a continuous air chamber, the top of

the casing being open and the top of the wall being closed, an inwardly extending projection at the upper edge of the wall 15 formed with a continuous channel, a cover fitting upon the top of the wall and formed with a flange fitting within said channel, and clamping bolts passing through the cover and the top of said wall. 20

In testimony whereof I affix my signature.

ALBERT BRUCE TUCKER.
